John A. Tracy, Attorneys.

UNITED STATES PATENT OFFICE.

GEORGE HARRIS, OF DYERSBURG, TENNESSEE.

RAIL-JOINT.

1,198,724.

Specification of Letters Patent. Patented Sept. 19, 1916.

Application filed November 23, 1915. Serial No. 62,088

To all whom it may concern:

Be it known that I, GEORGE HARRIS, a citizen of the United States, residing at Dyersburg, in the county of Dyer and State of Tennessee, have invented certain new and useful Improvements in Rail-Joints, of which the following is a specification.

This invention contemplates an improved rail joint and has as its primary object to provide a construction wherein the meeting ends of the rails will be securely and firmly connected and wherein the use of fish plates as well as bolts or other similar fastening devices for joining the rail ends will be eliminated.

The invention has as a further object to provide a construction wherein the coacting rail ends will be provided with interengaging overlapping portions mating to form a connection between the said rail ends and further to provide an arrangement wherein the coacting ends of the rails may, when desired, be readily connected or disconnected. And a still further object of the invention is to provide an improved joint of this character wherein the coacting ends of the rails will be formed to receive a chair plate extending longitudinally beneath the joint and arranged to counteract any tendency of the coacting ends of the rails to shift relative to each other under the weight of a load.

Other and incidental objects will appear as the description proceeds and in the drawings wherein I have illustrated the preferred embodiment of the invention and wherein similar reference characters designate corresponding parts throughout the several views. Figure 1 is a fragmentary side elevation showing the coacting ends of a pair of rails provided with my improved joint and illustrating the manner in which the chair plate employed is arranged to extend beneath the meeting terminals of the base flanges of the rails. Fig. 2 is a fragmentary perspective view showing the meeting ends of the rails and more particularly illustrating the construction of the joint, and Fig. 3 is a horizontal sectional view showing the manner in which the locking members of one rail end are adapted to engage within the sockets of the other rail end.

Referring more particularly to the drawings, I have illustrated the coacting ends of a pair of rails A and B respectively formed

in accordance with the present invention. 55 The rail A includes a tread 10, a web 11, and a base flange 12. The tread 10, at the adjacent extremity of the rail is extended to provide an overhanging terminal 13 from which depend longitudinally spaced substantially 60 dovetail locking members 14 each provided with oppositely disposed lateral shoulders 15. The web 11 at the inner extremity of the overhanging terminal 13, is provided with an enlarged or laterally thickened 65 portion 16 which is formed upon opposite sides thereof with longitudinally extending grooves 17 sloping away from the upper edge of the base flange 12. The rail B also includes a tread 18, a web 19, and a base 70 flange 20.

At the adjacent extremity of the rail B, the tread 18 thereof is cut away while the web 19 is formed with a laterally thickened portion 21 providing a terminal extending 75 longitudinally beyond the contiguous end of the tread and substantially equal in length to the length of the overhanging terminal 13 of the rail A, the terminal 21 being formed with a flat upper face to receive 80 the terminal 13. The thickened portion 21 of the rail B is provided with longitudinally spaced dovetail sockets 22 adapted to removably receive the locking members 14 of the overhanging terminal 13 of the rail 85 A. Each of the said sockets is provided with oppositely disposed lateral shoulders 23 adapted to cooperate with the shoulders 15 of the said locking members. Formed in opposite sides of the thickened portion 21 90 of the rail B are longitudinally extending grooves 24 substantially identical with the grooves 17 of the rail A and adapted to register therewith, the grooves 24 sloping away from the upper edges of the base flange 20 95 of the rail.

In Figs. 1 and 3 of the drawings, I have shown the manner in which the adjacent ends of the rails are adapted to coact for connecting the rails. The locking members 100 14 of the rail A are received within the sockets 22 of the rail B with the overhanging terminal 13 of the rail A seating flatly against the upper face of the thickened terminal 21 of the rail B. It will be noted that 105 the sockets 22 are of such dimensions as to permit the locking members 14 to shift from side to side within the said sockets to thus

compensate for any expansion or contraction of the rails brought about by climatic conditions. Normally, the locking members 14 will engage within the sockets 22 as best shown in Fig. 3 of the drawings with corresponding shoulders 15 of the said locking members engaging corresponding shoulders 23 of the said sockets. When in this position the adjacent inclined edges of the locking members 14 will engage the confronting inclined walls of the sockets 22 to prevent any vertical shifting of the locking members 14 within the said sockets so that the coacting ends of the rails will be securely joined. 10 Should the rails be caused to contract, the locking members 14 will move within the sockets 22 to engage corresponding shoulders 15 thereof with the corresponding shoulders 23 of the said sockets shown idle 15 in Fig. 3, so that a secure connection between the rail ends will be insured. By manually shifting the rail ends relative to each other to such position that the locking members 14 will be disposed medially of the sockets 22, the coacting ends of the rails may be 20 easily disconnected since the locking members may then be withdrawn from the said sockets.

Arranged beneath the base flanges of the rails at the junction thereof, is a chair plate 25 which is provided with coacting inwardly curved flanges 26 embracing opposite edges of the base flanges of the rails to fit snugly within the registering grooves 17 and 24 thereof and thus engage the rail ends upon opposite sides, as more particularly shown in Fig. 1. It will be noted that the chair plate 25 will provide a rigid support for the meeting ends of the flanges 12 and 20 of the rails 25 acting to overcome any tendency of the rails to shift vertically relative to each other at the coacting ends thereof while the flanges 26 in abutting opposite sides of the rail ends, will act to overcome any tendency of the coacting extremities of the rails to shift laterally relative to each other. Furthermore, these flanges 26 will also tend to prevent spreading of the rails of a track at the joints between each of the rails. It will therefore 30 be seen that the chair plate 25 will effectually coöperate with the locking members 14 and the sockets 22 of the rail ends to provide a secure and firm connection between the rails.

The joint is simple in construction and it 35 will be noted that the use of fish plates as well as other fastening devices for connecting the rail ends, is eliminated.

Having thus described my invention, what I claim and desire to secure by Letters Patent is:

1. In a device of the character described, coacting rail ends, one provided with an overhanging tread portion having coacting locking members depending therefrom and 40 having its web thickened at the inner ex-

tremity of said overhanging tread portion, there being grooves formed in the thickened portion of the web upon opposite sides thereof, and the other rail end having its head cut away and provided with a thickened 70 web portion having coacting sockets formed therein to receive the coacting locking members of the overhanging tread portion of said first mentioned rail end with the overhanging tread portion seating upon the 75 thickened portion of the said second mentioned rail end, the said thickened portion of the second mentioned rail end having grooves formed in opposite sides thereof adapted to register with said first mentioned 80 grooves, and a chair plate engaging beneath the meeting ends of the rail flanges and provided with flanges engaging in said grooves.

2. In a device of the character described, 85 coacting rail ends, one having its tread portion cut away and provided in its web portion with a socket having a lateral bearing shoulder formed in a wall thereof and the other being provided with an overhanging 90 tread portion adapted to seat in the cut away portion of said first mentioned rail end and provided with a locking member receivable in said socket and formed with a lateral bearing shoulder, the said locking member 95 being shiftable within the said socket to active position connecting the rail ends with the shoulder of the locking member engaging the shoulder in the wall of the 100 socket.

3. In a device of the character described, coacting rail ends, one having an overhanging tread portion provided with a dove-tailed locking member having a lateral bearing shoulder and the other having its tread 105 portion cut away to receive the tread portion of said first mentioned rail end and provided in its web portion with a recess adapted to receive said locking member to coact therewith, there being a bearing shoulder 110 formed in a wall of said recess and the said locking member being shiftable to active position within the said recess connecting the said rail ends with the shoulder of the locking member engaging the shoulder in 115 the said recess wall.

4. In a device of the character described, coacting rail ends, one having the tread portion thereof cut away and provided in its web portion with a dove-tailed socket and the other provided with an overhanging 120 tread portion adapted to seat within the cut away portion of the said first mentioned rail end and provided with a dove-tailed locking member receivable within the said 125 socket and shiftable therein to active position connecting the said rail ends.

5. In a device of the character described coacting rail ends, one having an overhanging 130 tread portion provided with a locking

member and the other having its tread portion cut away to receive the overhanging portion of said first mentioned rail end in overlapping relation and provided with a 5 recess adapted to receive said locking member to coact therewith, the webs of said rail ends being provided with grooves upon opposite sides thereof, and a chair plate associated with the meeting terminals of

said rail ends and provided with flanges engaging in said grooves.

In testimony whereof I affix my signature.

GEORGE ^{his} X HARRIS.
